(57) **ABSTRACT**

Exemplary embodiments of a composite pallet with augmented compression support may comprise a pallet pulp body, a multiplicity of support foot sheaths, and a support bottom plate. The pallet pulp body may be comprised of pulp and may have an upper faceplate and a plurality of support feet disposed oppositely of the upper faceplate. A foot cavity may be defined within each support foot. Each of the support foot sheaths may envelope at least a portion of a corresponding support foot. The support bottom plate may be affixed to two or more of the support foot sheaths. A plurality of arcuate stiffener grooves may be disposed in the upper faceplate. One or more of the foot cavities may have a compression column disposed therein. Each compression column may comprise one or more column layers, a compression column block, or a combination thereof. The column layers may be nested.

**COMPOSITE PALLET WITH AUGMENTED
COMPRESSION SUPPORT, AND PROCESS
FOR MANUFACTURING SAME**

RELATED APPLICATIONS

This application is a U.S. national stage of PCT International Patent Application No. PCT/US2023/081224 having an international filing date of Nov. 27, 2023, which claims the benefit of U.S. Provisional Patent Application No. 63/521,472 filed Jun. 16, 2023. The contents of the above-identified applications are incorporated by this reference in their entirieties for all purposes as if fully set forth herein.

TECHNICAL FIELD

The present disclosure relates to pulp molded products, and the systems and processes by which they are manufactured.

BACKGROUND

Load-bearing plates, often referred to as pallets, are very important tools for modern industrial and commercial production, transportation, storage and packaging. With the development of the logistics industry, more and more load-bearing plates are used for storing goods and moving goods. Take the common pallet as an example, which are most typically made of a single, homogeneous material such as wood, steel, plastic or pulp.

Conventional pulp pallet processing technology typically involves the transfer about 2% pulp to the drying part of the manufacturing equipment for drying after molding and vacuum dewatering. Due to the limitations of most conventional pulp materials, the water resistance, compressive strength of the product is low, and durable strength is limited.

SUMMARY

Certain deficiencies of the prior art are overcome by the provision of a composite pallet with augmented compression support, and process for manufacturing same, as disclosed herein.

For example, a pallet pulp body may have support (base) feet first covered with a plastic pressure sheath (otherwise referred to herein as a support foot sheath). The plastic pressure sheath may be pre-formed, for example, in an injection molding machine, and may be composed of material such as, for example, recycled PE plastic. Moreover, a prefabricated film (referred to herein as an upper film layer) may be attached to the upper surface of the pallet pulp body, and may also be comprised of, for example, recycled PE. Once in alignment with one another, these three layers (pallet pulp body, support foot sheaths, and upper film layer) may then be pressed and formed on a hot-pressing machine.

In certain preferred implementations of the invention, support compression columns may be provided for insertion into the foot cavity of each of the support feet. According to the desired compressive strength grade of the composite pallet, the supporting foot compressive columns may comprise different forms of layering. For example, one or more column layers may be successively added to one or more foot cavities of the pallet. There may be, for example, three forms of support foot compression column: semi-closed foot

2

multi-layer compression column, sleeve-type foot multi-layer compression column, and single-block type foot compression column.

5 BRIEF DESCRIPTION OF THE DRAWINGS

Further advantages of the present invention may become apparent to those skilled in the art with the benefit of the following detailed description of the preferred embodiments 10 and upon reference to the accompanying drawings in which:

FIG. 1 is a diagrammatic top view of one non-limiting example of a pallet pulp body;

FIG. 2 is a diagrammatic cross-sectional view taken along lines 2-2 in FIG. 1;

FIG. 3 is a diagrammatic top view of one non-limiting example of an upper film layer;

FIG. 4 is a diagrammatic cross-sectional view taken along lines 4-4 of FIG. 3;

FIG. 5 is a diagrammatic top view of one non-limiting example of a support foot sheath;

FIG. 6 is a diagrammatic cross-sectional view taken along lines 6-6 of FIG. 5;

FIG. 7A is a diagrammatic top view of one non-limiting 25 example of a support bottom plate in planar form;

FIG. 7B is a diagrammatic top view of another non-limiting example of a support bottom plate in planar form but wherein the plate includes a bottom plate aperture;

FIG. 8 is a diagrammatic exploded cross-sectional view of 30 the example composite pallet of FIG. 11, taken along lines 2-2 of FIG. 1, illustrating the relevant components prior to being combined in a hot-press mold system;

FIG. 9 is a diagrammatic cross-sectional view of a hot-press mold system with the upper and lower hot press molds 35 shown separated from one another;

FIG. 10 is a diagrammatic cross-sectional view illustrating the composite pallet components of FIG. 8 being pressed and formed in the hot-press mold system of FIG. 9;

FIG. 11 is a diagrammatic cross-sectional view of an 40 example composite pallet without compression columns;

FIG. 12 is a magnified view of detail 12 in FIG. 10;

FIG. 13 is a magnified view of detail 13 in FIG. 11;

FIG. 14 is a diagrammatic exploded cross-sectional view 45 of one non-limiting example of a compression column, wherein the compression column includes a compression column block and three sequentially nestable column layers having closed bottoms;

FIG. 15 is a diagrammatic cross-sectional view illustrating 50 compression columns formed from the components shown in FIG. 14 being inserted into the pallet substructure similar to that of FIG. 11, thereby augmenting the compression strength of resulting composite pallet;

FIG. 16 is a diagrammatic cross-sectional view of an 55 example composite pallet resulting from the assembly step illustrated in FIG. 15;

FIG. 17 is a magnified view of detail 17 in FIG. 16;

FIG. 18 is a diagrammatic exploded cross-sectional view of another non-limiting example of a compression column, 60 wherein the compression column includes a compression column block and three sequentially nestable column layers having open bottoms;

FIG. 19 is a diagrammatic cross-sectional view illustrating 65 compression columns formed from the components shown in FIG. 18 being inserted into the pallet substructure similar to that of FIG. 11, thereby augmenting the compression strength of resulting composite pallet;

FIG. 20 is a diagrammatic cross-sectional view of an example composite pallet resulting from the assembly step illustrated in FIG. 19;

FIG. 21 is a magnified view of detail 21 in FIG. 20;

FIG. 22 is a side view of an example composite pallet in accordance with the present disclosure, wherein the pallet is shown supportingly disposed between a load and a substrate surface, thereby imposing a compression force on the pallet based on the weight of the load;

FIG. 23 is a diagrammatic cross-sectional view illustrating compression columns formed exclusively of compression column blocks being inserted into the pallet substructure similar to that of FIG. 11, thereby augmenting the compression strength of resulting composite pallet;

FIG. 24 is a diagrammatic cross-sectional view of an example composite pallet resulting from the assembly step illustrated in FIG. 23; and

FIG. 25 is a magnified view of detail 25 in FIG. 24.

DETAILED DESCRIPTION OF THE PREFERRED EMBODIMENTS

Referring now to the drawings, like reference numerals designate identical or corresponding features throughout the several views.

Certain example embodiments of a composite pallet with augmented compression support are shown generally at 100, for example in FIGS. 11, 16 and 20. Referring to FIGS. 8, 11 and 13, preferred embodiments of the composite pallet 100 may comprise a pallet pulp body 102, an upper film layer 104, a multiplicity of support foot sheaths 106, and a support bottom plate 108.

Referring to FIGS. 1 and 2, the pallet pulp body 102 may be comprised of pulp and may have an upper faceplate 120 and a plurality of support feet 118 disposed oppositely of the upper faceplate 120. A foot cavity 124 may be defined within each support foot 118, and a foot bottom 126 may be defined oppositely of the foot cavity 124. The pallet pulp body 102 may preferably be comprised of pulp, and may have a wall thickness 122 of, for example, 9-15 millimeters (see, e.g., FIG. 2).

Referring to FIGS. 5, 6, 8 and 13, the multiplicity of support foot sheaths 106 may envelop at least a portion of a corresponding one of the support feet 118. Referring to FIG. 6, in certain preferred implementations of the composite pallet 100, each of the support foot sheaths 106 may have a sheath bottom 150 disposed oppositely of a sheath cavity 148. Referring to FIG. 13, in such implementations, the envelopment of the support foot 118 by the support foot sheath 106 may be by way of the sheath cavity 148 receiving the corresponding support foot 118. Indeed, in certain cases there may be an offset distance 164 between the upper faceplate 120 and the sheath periphery 152. The support foot sheaths 106 may preferably have a wall thickness 168 of, for example, 1-5 millimeters.

Referring to FIGS. 8, 11 and 13, a support bottom plate 108 may be affixed to two or more of the support foot sheaths 106. In particular, in certain implementations of the composite pallet 100, the support bottom plate 108 may be affixed to the sheath bottoms 150 of the respective support foot sheaths 106. Referring to FIG. 7B, in particular implementations of the composite pallet 100, the support bottom plate 108 may have a bottom plate aperture 142, and may only be affixed to support foot sheaths 106 that are disposed peripherally about the pallet pulp body 102 (e.g., most proximate to pulp body periphery 130). Such peripherally-disposed support foot sheaths 106 may be defined as those

that envelop peripherally-disposed support feet, such as those support feet labeled as 118' in FIGS. 1 and 2. Alternatively, referring to FIGS. 7A and 11, in certain preferred implementations of the composite pallet 100, the support bottom plate 108 may be flat planar without any large apertures, and resultingly may be affixed to all of the support foot sheaths 106, whether peripherally-disposed or not.

Referring to FIG. 1, in particular preferred implementations of the composite pallet 100 the pallet pulp body 102 may include 9 or 12 of the support feet. Additionally or in the alternative, the pallet pulp body 102 may include straight stiffener channels 128a disposed between one or more adjacent pairs of support feet 118 (for example between pairs of peripherally-disposed support feet 118'). Moreover, a plurality of arcuate stiffener grooves 128b may be disposed in the upper faceplate 120, and two or more of these arcuate stiffener grooves may be arranged concentrically with one another (as shown, for example, in FIG. 1). The straight stiffener channels 128a and the arcuate stiffener channels 128b may preferably have a channel depth 144 of 20-50 millimeters. Furthermore, at least one adjacent pair of arcuate stiffener channels 128b may have a channel spacing 146 of, for example, 80-120 millimeters. Most preferably, the channel spacing may be about 100 millimeters.

Referring to FIGS. 11 and 13, in implementations of the composite pallet 100 which comprise an upper film layer 104, such upper film layer may be disposed on the pallet pulp body 102, and may extend along the upper faceplate 120 and within the foot cavities 124. The upper film layer 104 is preferably waterproof, and may be made of recycled PE plastic or the like.

Referring to FIGS. 16, 20 and 24, certain preferred implementations of a composite pallet 100 may further comprise a multiplicity of compression columns 166. Each compression column may be disposed within the foot cavity 124 of a respective support foot 118. Referring to FIGS. 17, 21 and 25, each compression column 166 may include a compression column block 110. In particular implementations of a composite pallet 100 with compression columns 166, each compression column 166 may include a first column 112 layer disposed between the compression column block 110 and the respective foot cavity 124. Moreover, each compression column 166 may include a second column layer 114 disposed between the first column layer 112 and the compression column block 110. Furthermore, each compression column 166 may include a third column layer 116 disposed between the first column layer 112 and the compression column block 110.

Referring to FIGS. 18 and 21, in certain implementations of a composite pallet 100 with compression columns 166, one or more of the column layers (112, 114, 116) may have open bottoms (132, 134, 136). This may be referred to as a nested-sleeve configuration for a compression column 166.

Referring to FIGS. 14 and 17, in certain implementations of a composite pallet 100 with compression columns 166, one or more of the column layers (112, 114, 116) may have closed bottoms (132, 134, 136). This may be referred to as a nested-cup configuration for a compression column 166.

In particular implementations of a composite pallet 100 with compression columns 166, the compression column blocks 110 and column layers (112, 114, 116) may be comprised of a material selected from the group consisting of plant fiber, synthetic fiber, metal, wood and plastic. Moreover, referring to FIG. 14, the column layers may preferably have a wall thicknesses 170 of, for example, 9-15 millimeters.

Certain additional details regarding a process for manufacturing the composite pallet **100** are provided below.

The pallet pulp body **102**, such as that shown in FIGS. 1 and 2, may be fabricated on a pulp molding machine. The resulting thickness of the pallet pulp body **102** may preferably be, for example, 9-15 mm. The pallet pulp body may preferably comprise or consist of 9 or 12 pallet support feet **118**. Grooves (otherwise referred to herein stiffener channels) may be connected with the supporting feet around the pallet pulp body **102**, which can greatly strengthen the compressive and flexural strength of the resulting composite pallet.

The column layers (**112**, **114**, **116**) may also be made on a pulp molding machine, and then inserted into the foot cavities of the pallet pulp body **102**. Their individual or collective wall thickness may be, for example, 9-15 mm. The single block type foot compression column **110** may be, for example, die-cast once in a block press.

The upper film layer **104** may be formed as shown in, for example, FIGS. 3 and 4. This upper film layer **104** may preferably be formed from recycled PE plastic, in an injection molding machine. The primary function of this upper film layer **104** is to provide waterproofing and to increase the surface strength of the pallet.

Regarding the production of the support foot sheath **106**, these are preferably comprised of a plastic and may be formed as shown in FIGS. 5 and 6. These too may be made from raw material such as recycled PE plastic, and may be formed in an injection molding machine. The primary functions of these sheaths **106** are to provide waterproofing and to increase the rigidity of the pallet support feet. The average wall thickness of these support foot sheaths **106** may preferably be 1-5 mm.

Referring to FIGS. 7A and 7B, the support bottom plate **108** may be of, for example, two types. The first type, represented for example in FIG. 7A, may be a fully enclosed bottom plate. In contrast, the second type, represented in FIG. 7B, may be a semi-enclosed bottom plate with, for example, one or more bottom plate apertures **142**. The first type of bottom plate **108** can be glued (other otherwise affixed) to all of the support foot sheaths **106** of the pallet, which in turn can raise the strength of the pallet to the highest strength, suitable for the static load of, for example, more than 1000 kg. The second type of bottom plate **108** may be glued, for example, to just the support foot sheaths **106** disposed at the periphery of the pallet. These support bottom plates **108** may preferably be made of a raw material mainly comprising recycled PE plastic, and can also be produced using a conventional injection molding machine.

Referring to FIGS. 8-10, the bottom plate **108**, support foot sheaths **106**, the pulp body **102** and the upper film layer **104** can be placed into the lower mold **158** of a hot press machine. The upper mold **156** falls and closes with the lower mold **158**. As shown in FIG. 10, the upper and lower molds are pressed together at, for example, 90° C. for several seconds. The molds are then pulled apart and the resulting pallet product is removed, as illustrated for example in FIG. 11.

After removing the pallet substructure **154** from the hot press mold, depending upon the desired compression resistance of the composite pallet **100**, one of several different forms of foot compression columns **166** may be set in the foot cavities of the pallet support feet **118**. For example, each compression column **166** in the composite pallet shown in FIGS. 16 and 17 may include three sets of column layers (**112**, **114**, **116**) with a compression column block **110**, and may thereby enable the resulting composite pallet **100** to

sustain a load weight of, for example, 6000 kg. The same pallet load rating may be achieved with the composite pallet configurations shown in FIGS. 24 and 25, wherein the compression columns **166** are only comprised of a single compression column block **110** without column layers added. A pallet load rating of, for example, 4000 kg may be achieved by employing compression columns **116** with three column layers (e.g., **112**, **114**, **116**) and without any compression column block **110**. A pallet load rating of, for example, 2000 kg may be achieved without employing any compression columns **116**.

Applicant has conducted at least one load test of the composite pallet **100** configuration illustrated in FIG. 16, wherein the following components were comprised merely of paper pulp: pallet pulp body **102**, support foot sheath **106**, support bottom plate **108**, compression column block **110**, first column layer **112**, second column layer **114** and third column layer **116**. In this test, the composite pallet **100** was successfully subjected to a static load **140** of 6 metric tons (13227 pounds) for a period of 4.5 months. It is anticipated that using materials other than or in addition to paper pulp could increase the load bearing performance of the composite pallet **100** well beyond the 6 tons demonstrated during testing.

The following listing matches certain terminology used within this disclosure with corresponding reference numbers used in the non-limiting examples illustrated in the several figures.

- 100** composite pallet with augmented compression support
- 102** pallet pulp body
- 104** upper film layer (e.g., recycled PE plastic)
- 106** support foot sheath
- 108** support bottom plate
- 110** compression column block
- 112** first column layer (e.g., sleeve or cup configuration)
- 114** second column layer (e.g., sleeve or cup configuration)
- 116** third column layer (e.g., sleeve or cup configuration)
- 118** support foot
- 118'** peripherally-disposed support foot
- 120** upper faceplate (of pallet pulp body)
- 122** pulp body wall thickness (e.g., 9-15 millimeters)
- 124** foot cavity (of support foot)
- 126** bottom of foot
- 128a** straight stiffener channel
- 128b** arcuate stiffener channel (e.g., multiple concentric)
- 130** pulp body periphery
- 132** bottom of first column layer
- 134** bottom of second column layer
- 136** bottom of third column layer
- 138** main axis (of pallet)
- 140** load (e.g., bearing it weight on pallet **100**)

- 166** compression column

168 sheath wall thickness (e.g., 1-5 millimeters)

170 column layer wall thickness (e.g., 9-15 millimeters)

While embodiments of the invention have been illustrated and described, it is not intended that these embodiments illustrate and describe all possible forms of the invention. Rather, the words used in the specification are words of description rather than limitation, and it is understood that various changes may be made without departing from the spirit and scope of the invention.

What is claimed is:

1. A composite pallet with augmented compression support, the pallet comprising:
  - a pallet pulp body being comprised of pulp and having an upper faceplate and a plurality of support feet disposed oppositely of the upper faceplate, a foot cavity being defined within each support foot;
  - a multiplicity of support foot sheaths, each support foot sheath enveloping at least a portion of a corresponding one of said support feet; and
  - a support bottom plate affixed to two or more of the support foot sheaths;
  - wherein the support bottom plate
    - (a) has a bottom plate aperture, and
    - (b) is only affixed to support foot sheaths disposed peripherally about the pallet pulp body.
2. A composite pallet with augmented compression support, the pallet comprising:
  - a pallet pulp body being comprised of pulp and having an upper faceplate and a plurality of support feet disposed oppositely of the upper faceplate, a foot cavity being defined within each support foot;
  - a multiplicity of support foot sheaths, each support foot sheath enveloping at least a portion of a corresponding one of said support feet;
  - a support bottom plate affixed to two or more of the support foot sheaths; and
  - a multiplicity of compression columns, each compression column being disposed within the foot cavity of a respective said support foot;
  - wherein each compression column includes a compression column block;

wherein each compression column includes a first column layer disposed between the compression column block and the respective foot cavity; and

wherein each compression column includes a second column layer disposed between the first column layer and the compression column block.

3. The composite pallet of claim 2, wherein each compression column includes a third column layer disposed between the first column layer and the compression column block.

4. A composite pallet with augmented compression support, the pallet comprising:

a pallet pulp body being comprised of pulp and having an upper faceplate and a plurality of support feet disposed oppositely of the upper faceplate, a foot cavity being defined within each support foot;

a multiplicity of support foot sheaths, each support foot sheath enveloping at least a portion of a corresponding one of said support feet;

a support bottom plate affixed to two or more of the support foot sheaths; and

a multiplicity of compression columns, each compression column being disposed within the foot cavity of a respective said support foot;

wherein each compression column includes

- (a) a first column layer disposed within the respective foot cavity,
- (b) second column layer disposed within the first column layer, and
- (c) a third column layer disposed within the second column layer.

5. The composite pallet of claim 4, wherein each column layer has an open bottom.

6. The composite pallet of claim 4, wherein each column layer has a closed bottom.

7. The composite pallet of claim 2, wherein each compression column block and column layer is comprised of a material selected from the group consisting of plant fiber, synthetic fiber, metal, wood and plastic.
